UNITED STATES PATENT OFFICE.

CHRISTIAN H. T. HAGELSTEIN, OF BOSTON, MASSACHUSETTS, ASSIGNOR TO THE REECE BUTTON HOLE MACHINE COMPANY, OF BOSTON, MASSACHUSETTS, A CORPORATION OF MAINE.

STOP MOTION.

Application filed March 14, 1922. Serial No. 543,577.

To all whom it may concern:

Be it known that I, CHRISTIAN H. T. HAGELSTEIN, a citizen of the United States, and resident of Boston, county of Suffolk, State 5 of Massachusetts, have invented an Improvement in Stop Motions, of which the following description, in connection with the accompanying drawing, is a specification, like characters on the drawing representing like parts.

This invention relates to stop motions for machines which are constructed to perform a pre-determined cycle of operations and then come to rest automatically, and the 15 principal object of the invention is to provide an improved stop motion which is capable of use with machines operating at high speed and which will function to bring the machine to rest at the end of the cycle 20 of operations with a cushioned movement, thus eliminating any jar or shock which is detrimental to the machine.

In order to give an understanding of the invention I have illustrated in the drawings 25 a selected embodiment thereof which will now be described after which the novel features will be pointed out in the appended claims.

Fig. 1 shows in elevation a portion of a 30 machine having one form of my improved stop motion applied thereto.

Fig. 2 is a top plan view of Fig. 1.

Fig. 3 is a side elevation.

Fig. 4 is a bottom plan view of a portion 35 of the machine to which the stop motion is applied and showing the under side view of the stop motion.

Fig. 5 is a detail of the cam for releasing the locking member.

40 Figs. 6 and 7 are end views showing the stop cam and a portion of the stop dog, in different positions.

Fig. 8 is a view of the housing enclosing the spring which controls the recoil preventing latch.

Fig. 9 is a section on the line 9—9, Fig. 6.

My improved stop motion is adapted to be used in connection with a great variety of machines that are constructed to perform 50 a pre-determined cycle of operations and then to come to rest, and merely as illustrating a machine of this type I would refer to sewing machines that are adapted to sew a short seam and then come to rest.

55 I wish to have it clearly understood, how-

ever, that my invention is applicable to a variety of machines and is not confined in its use to any particular machine.

The invention herein shown is in some respects similar to the device shown in United States Patent No. 1,173,162, Feb. 29, 1916.

In the drawings I have illustrated at 1 a portion of the frame of a machine with which the stop motion is associated, said machine being of the type which is provided with a drive shaft 2 by which it is operated. This drive shaft is shown as having a fast and loose pulley thereon, 3 indicating the loose pulley which is loosely mounted on the shaft, and 4 indicating the fast pulley 70 which is rigid with the shaft.

Co-operating with the pulleys is a driving belt 5 which is adapted to be shifted from the loose pulley to the fast pulley and vice versa by means of a belt shipper 75 6. This belt shipper is carried by an arm 7 which is fast on a rock shaft 8 journalled in suitable bearings 9 carried by the frame 1. The turning of the rock shaft operates through the belt shipper 6 to shift the belt 80 from the loose pulley to the fast pulley to start the machine and from the fast pulley to the loose pulley to stop the machine.

Means are provided for turning the rock shaft manually to start the machine, such 85 means comprising a hand lever 49 fast to the shaft and by which the shaft may be turned by hand, and also comprising an arm 10 fast to and extending laterally from the shaft and to which a foot treadle may be 90 attached by a connection 11.

When the shaft has been turned to throw the belt onto the fast pulley, as shown in the drawings the belt shipper is locked in its position by means of a latch 12 pivotally 95 mounted on an arm 13 carried by the frame and acted upon by a spring 14 which tends to hold it in operative position. This latch is released automatically at the end of the cycle of operations by means of a releasing 100 cam 15 which is secured to and rotates with the main cam 16 of the machine, the latter being connected to and driven by the driving shaft 2. For this purpose the latch 12 has integral therewith an arm 17 having a 105 cam face 18 engaged by the releasing cam 15 at a pre-determined point in the cycle of operations.

When the latch 12 is released the rock shaft 8 is turned to shift the belt into the 110

dotted line position thereby to carry the belt onto the loose pulley by means of one or more springs 19 which are situated between the frame 1 and a bracket or frame 20 that is rigid with the rock shaft 8.

The parts thus far described are or may be all as usual in said above-mentioned patent.

For bringing the shaft 2 to rest when the belt shipper is thrown onto the loose pulley I provide a stop cam 21 which is fast on the shaft 2 and which co-operates with a stop dog 22 slidably mounted in bearings 23 formed on the frame 20 and acted upon by a spring 24 tending to move it toward the stop cam. This spring 24 surrounds the shank 25 of the stop dog and is confined between a collar 26 adjustable on said shank and one of the bearings 23. The collar 26 co-operates with the other bearing 23 to limit the spring-impelled movement of the stop dog.

When the parts are in the position shown in Fig. 2 with the belt on the fast pulley the stop dog 22 is situated out of line with the stop cam 21. As soon as the latch 12 is released at the proper point in the cycle of operations, the frame 20 is moved into the dotted line position Fig. 2 by the springs 19 thereby bringing the stop dog into the path of the stop cam 21.

The stop cam 21 is shown as having a high point 27 and as having an eccentric curved face 28 on the back-side of the high point and a straight face 29 on the front side of the high point.

In order to bring the shaft 2 to rest with a cushioned movement and without any appreciable shock or jar I have designed the parts so that after the latch is released and the stop dog is moved into the path of the stop cam 21 said shaft will make one complete revolution thus carrying the point 27 of the cam, as shown in Fig. 6, past the stop dog once and will then come to rest with the stop dog against the straight face 29 of the cam during the next revolution, as shown in Fig. 7.

The parts are timed so that when the latch is released and the stop dog is moved into the path of the cam the cam will be approximately in a position with the low portion of the cam opposite said stop dog. As the cam continues to rotate due to the momentum of the machine the face 29 of the cam will engage the end of the stop dog 22 thus forcing the stop dog backwardly against the action of the spring 24.

The shape of the cam is such, with relation to the tension of the spring 24, that the momentum of the rapidly moving parts will carry the high point of the cam past the end of the stop dog, as shown in Fig. 6, thus fully compressing the spring 24. The tension of the spring is such that the resistance

it offers to the movement of the cam while the face 29 is wiping past the end of the stop dog will very materially reduce the momentum of the parts without, however, bringing the shaft entirely to rest. As soon as the high point of the cam passes the high point of the stop dog then the latter will move down the eccentric face 28 and during the expanding movement of the spring 24 will have a tendency to keep the shaft turning. When the shaft arrives at the position shown in Fig. 7 the momentum of the parts will be so far reduced that the engagement of the face 29 and the stop cam a second time with the end of the stop dog 22 will bring the machine to rest with an easy movement.

It will thus be seen that with this construction the first rotation of the shaft 2 after the belt has been shifted onto the loose pulley will very materially reduce the momentum of the parts without bringing the shaft to rest, and that the final stoppage of the machine occurs when the face 29 of the cam a second time engages the end of the stop dog 22.

In order to prevent any rebound after the machine has come to rest I provide a stop latch 30 which is pivoted in the side of a cup-shaped disk 31 that is fast on the shaft 2 and is situated adjacent the stop cam 21. This latch 30 is acted upon by a spring 32 which tends to hold it in its operative position and said latch is formed with the finger or extension 33 which limits the spring-impelled movement thereof. The latch is shown as operating in an opening 34 in the disk 31 and as pivoted on the radial pivot 35. This can be readily pushed inwardly against the action of the spring in the direction of the arrow, Fig. 9, and during the rotation of the shaft 2 after the stop dog has been moved into the path of the cam, said stop dog will wipe over the latch 30 and the latter will be retracted against the action of the spring 32 as the stop dog passes it. When the stop dog has passed over the latch 30, however, it springs outwardly behind the dog, as shown in Fig. 7 and thus prevents any rebound or backward movement of the shaft after it comes to rest.

The latch-releasing cam 15 is shown as mounted on a plate 36 which is adjustably secured to the cam 16 and is held in position by the clamping screw 37. With this construction the cam may be readily adjusted so that the latch will be released at the proper time.

I claim.

1. In a stop motion, the combination with a driving shaft, of a driving belt therefor and a belt shipper to connect the driving belt to or disconnect it from the shaft, of a stop cam fast on the driving shaft, said stop cam

- having a continuous peripheral cam face, said face being formed with a low portion, one end of which merges into a relatively-short straight portion of increasing radius 5 and the other end of which merges into a convexly-curved portion which is considerably longer than the straight portion and which also has a progressively-increasing radius, said straight portion and convexly- 10 curved portion meeting and forming a high point at the cam, a stop dog, a spring acting on the stop dog and adjustable as to its tension, said stop dog being connected to the belt shipper so that when the belt is connected 15 to the driving shaft the stop dog is out of the path of movement of the stop cam but when the belt is disconnected from the driving shaft the stop dog is carried into the path of movement of the stop cam and engages 20 the continuous cam face thereof, the shape of the cam face and the tension of the spring having such relation to the momentum and speed of the shaft that when the stop dog is brought into engagement with the cam the high point thereof will be carried past the stop dog once thereby largely reducing the speed of the shaft and said shaft will be brought to rest when the straight portion of the cam face comes a 25 second time into engagement with the stop dog.
2. In a stop motion, the combination with a driving shaft, a driving belt therefor and means to connect the driving belt to or disconnect it from the shaft, of a stop cam fast 35 on the driving shaft, said stop cam having a high point, a face of progressively diminishing radius on the front or forward side of the high point and a curved eccentric face also of progressively diminishing radius on 40 the back side of the high point, a spring-pressed stop dog, and means to cause the stop dog to engage the stop cam by the act of disconnecting the driving belt from the driving shaft, the shape of the stop cam and the 45 spring pressure on the stop dog having such relation to the momentum and speed of the shaft that when the stop dog is brought in to engagement with the cam the high point of the cam will be carried past the stop dog once 50 thereby largely reducing the speed of the shaft and said shaft will be brought to rest when the first-named face of the stop cam comes a second time into engagement with the stop dog, and a spring-pressed latch rotatable with the stop cam and adapted to engage the stop dog when the shaft comes to rest thereby to prevent rebound. 55

In testimony whereof, I have signed my name to this specification.

CHRISTIAN H. T. HAGELSTEIN.
